UNITED STATES PATENT OFFICE.

THOMAS SCRUTCHIN, OF ATLANTA, GEORGIA.

PUZZLE.

No. 895,114.

Specification of Letters Patent.

Patented Aug. 4, 1908.

Application filed February 20, 1908. Serial No. 416,904.

To all whom it may concern:

Be it known that I, THOMAS SCRUTCHIN, a citizen of the United States, residing at Atlanta, in the county of Fulton and State of Georgia, have invented certain new and useful Improvements in Puzzles; and I do hereby declare the following to be a full, clear, and exact description of the invention, such as will enable others skilled in the art to 10 which it appertains to make and use the same.

This invention relates to improvements in toys, and particularly to puzzles, and has for an object the provision of a puzzle that may 15 be formed in a plurality of different ways and yet be worked and constructed on the same general principle, and is designed to perplex anyone in properly solving.

Another object in view is the provision of a 20 plurality of blocks arranged in a plurality of shapes for forming a predetermined shape.

A further object in view is the provision of a puzzle that may be constructed of cardboard, wood, fiber, metal, or any other desired substance formed with a plurality of 25 triangles of various colors positioned thereon, the cardboard or other material being designed to be cut into a plurality of pieces with one or more of the triangles positioned 30 on or forming each piece.

A still further object in view is the provision of a puzzle that is attractive and instructive, and also requires considerable patience, acumen, and intellectual perseverance 35 to properly arrange the parts correctly for reforming the puzzle into an assembled condition.

With these and other objects in view the invention comprises certain novel constructions, combinations and arrangement of parts as will be hereinafter more fully described and claimed.

In the accompanying drawings: Figure 1 is a plan view of a puzzle positioned in a box 40 or casing. Fig. 2 is a plan view of the puzzle showing the parts slightly divided or separated, and the correct position of the same when in an assembled condition.

In forming a puzzle according to the present invention the same may be arranged in 50 any desired shape, but preferably I form the same triangular as seen in the accompanying drawing, in which, 1 indicates a puzzle, and 2

a box for receiving the same. The box or receptacle 2 is of considerable importance in arranging the parts of the puzzle, as the same receives and holds the various parts in the position in which they are placed when the puzzle is being solved. The puzzle may be made from any desired material, as cardboard, fiber, metal, wood, or like material, and arranged with a plurality of white triangular portions or spots 3, and a plurality of black triangular portions or spots 4. It will be evident of course that the portions or spots 3 and 4 may be of other color, but it is desirable to make the colors decidedly different in appearance so as to easily distinguish the same.

In constructing the puzzle the piece of 70 cardboard, or the like, is formed into a triangle, preferably an equilateral triangle, and then is constructed with the color portions 3 and 4 as seen in Fig. 1. The triangular piece of material is then cut into comparatively 75 small irregular portions, as seen in Fig. 2. The shape of the small portions or blocks, as shown in Fig. 2, may be varied, and consequently will vary the way the puzzle is worked so that when a puzzle cut out according to Fig. 2 has become familiar, the blocks may be cut out in a different way and it will require the same amount of work and perseverance for the person to solve the same as the original form requires.

In use after the various blocks have been formed, as seen in Fig. 2, the same are mixed up and then to solve the puzzle it is necessary to rearrange the same as seen in Figs. 1 and 2, so that one of the points of the triangles of 90 one color point upward and one of the points of the triangles of the other color point downward. The blocks may be cut out so as to permit the same to be rearranged and have one of the points of the black spots or portions pointing up, and one of the points of the white spots pointing downward.

In use this device may be used strictly as a toy or puzzle and afford amusement and form a pastime employment, or it may be used for 100 more serious purposes, as advertising various goods, the puzzle being used as an attractive feature.

What I claim is:

1. A puzzle comprising a set of blocks of 105 different shapes, each block having triangu-

lar spaces of different colors, and the blocks being so shaped as to adapt the set as a whole to be arranged in the form of a triangle.

2. A puzzle comprising a set of blocks of different shapes, each block having triangular spaces of different colors and the blocks being so shaped as to adapt the set as a whole to be arranged in the form of a triangle, and with one of the points of each space of a par-

ticular color pointing in one direction and 10 that of the other color in an opposite direction.

In testimony whereof I affix my signature in presence of two witnesses.

THOMAS SCRUTCHIN.
